UNITED STATES PATENT OFFICE.

PAUL SCHUYLER VAN BLOEM, OF HEMPSTEAD, NEW YORK, ASSIGNOR TO VIKING PRODUCTS CORPORATION, OF NEW YORK, N. Y., A CORPORATION OF NEW YORK.

ELEVATOR SIGNAL.

Application filed May 6, 1924. Serial No. 711,370.

This invention relates primarily to direction indicating signals which are designed to indicate the direction of travel of an elevator. Signals of this type commonly consist of a glass dome or bulb having an electric lamp arranged within it, the lamp being lighted by contacts operated by the elevator. These glass domes or bulbs are of different colors to indicate the up and down travel of the elevators.

The main object of this invention is to provide an elevator signal consisting of a glass receptacle or container with an electric light mounted therein and adapted to be lighted by the moving car, and to provide said glass receptacle or container with an exterior light-reflecting and deflecting surface so that when the electric lamp within the container is unlighted the exterior light rays will be reflected back from the surface of the container in such manner as to conceal the color of the glass and any indicating signal concealed within. This exterior light-reflecting surface is produced by a surface treatment of the glass and is of such character that when the electric lamp within the container is lighted the light rays from the lamp will pass outwardly through the glass container and completely destroy or obliterate the light-reflecting character of the exterior of the receptacle. By thus destroying the character of the light-reflecting surface of the glass receptacle, the true color of the glass appears. With the lamp extinguished the light-reflecting surface conceals the color of the glass and that color is only revealed by light rays passing through the receptacle.

Elevator signals are usually mounted in pairs, one indicating the up-travel of the elevator car and the other indicating the down-travel thereof. Up-and-down signals usually are differently colored, the up-signal being usually white although green frequently is used, and the down-signal being usually red, although other colors are sometimes used. It is one of the important objects of this invention to so treat the exteriors of the receptacles or containers that, with the lamps extinguished, both the up-and-down signals have the same general exterior appearance and the color of the glass is concealed until the signal lamp is lighted.

Glass having a luster finish or surface is now manufactured by a number of glass

making concerns in the United States. Two of the well known concerns making this glass are the Louis C. Tiffany Furnaces, Inc., of Corona, New York, and the Corning Glass Works of Corning, New York. It is a common article of commerce. Applicant does not know the exact method used in the production of this luster finish. Luster glass has an iridescent exterior surface which is brilliantly illuminated by light rays and said rays are reflected back from the surface in many beautiful colors. The exterior light-reflecting surface of luster finish might be compared with an iridescent oil and water film. The iridescence is brilliantly brought out by the reflected light rays, but wholly disappears when light rays are passed through the glass from the interior outwardly. The result of this is that while the interior of the receptacle is dark the exterior is brilliantly iridescent. When however, the interior of the receptacle is illuminated the iridescence disappears and the true color of the glass is disclosed. The iridescent exterior surface is produced in the manufacture of the glass and is not a film or coating merely applied to the exterior of the glass. The iridescence therefore is as permanent as the glass and is an integral part of the glass.

In the drawings, Figure 1 is a front elevation of an elevator signal constructed in accordance with this invention, and without interior illumination;

Fig. 2 a view similar to Fig. 1 showing the up signal illuminated by an enclosed lamp;

Fig. 3 a view similar to Fig. 1 showing the down signal illuminated by an enclosed lamp;

Fig. 4 a vertical longitudinal sectional view of the device shown in Fig. 1;

Fig. 5 a horizontal sectional view taken on the line 5-5 of Fig. 4;

Fig. 6 a front elevation of a different form of signal;

Fig. 7 a side elevation of the signal illustrated in Fig. 6; and

Fig. 8 a detail sectional view of a portion of the light receptacle or container showing its outer surface roughened or indented.

Referring to the various parts by numerals, 1 designates a base plate or frame adapted to be secured to a wall or other support. This supporting plate or frame may

85

95

105

110

be of any desired form. As shown it is illustrated as a sheet metal plate having an ornamental molding edge. The frame 1 carries the upper glass-holding frame 2 and 5 the lower glass holding frame 3. Intermediate these two glass holding frames is a central horizontal division wall 4 which is provided with a retaining flange 5 adapted to serve as means for retaining the glasses 10 in the holding frames 2 and 3. The division wall 4 separates the upper light-receptacle 6 from the lower light receptacle 7. Supported between the frame 2 and the wall 4 is a semi-cylindrical glass globe or container 8, 15 said globe forming the light receptacle or chamber 6. Within the chamber 6 is arranged an electric light bulb 9. The circuit wires from said light bulb pass through the plate 1, and are connected to the usual contact devices and electrical supply by means 20 of which the circuit will be completed through the lamp by the elevator at a certain point in its travel up and down in the elevator shaft. These devices may be of any 25 suitable form and it is thought to be unnecessary to illustrate them or to describe them herein. Supported between the frame 3 and the wall 4 is a semi-cylindrical glass globe or container 10, said globe forming 30 the light receptacle or chamber 7. Within the chamber 7 is arranged an electric light bulb 11. The circuit wires from said light bulb pass through the plate 1 and are connected ultimately to the usual contact devices carried by the car.

The globe 8 is provided with an "up" indicating character and the globe 10 is provided with a suitable "down" indicating character. These globes are preferably of 40 different colors. In the drawings the "up" indicating signal lens or globe 8 is shaded to indicate green and the "down" indicating globe 10 is shaded to indicate red.

The direction indicating characters are 45 shown in the form of arrows impressed in the inner surface of the glass so that the glass of the arrow is much thinner than the body of the globe. The purpose of this is to secure a more brilliant illumination of 50 the arrow than the body of the globe when the lamp is lighted, while at the same time the arrow will be of the same color as the globe but of a lighter shade.

The exterior surfaces of the globes are 55 made rough with minute indentations in order to cover the entire surface of the globe with a multiplicity of small light reflecting surfaces at angles to each other. These surfaces might be produced by pressing soft glass into contact with a sanded, mottled, irregular or pebbled surface so that the glass is given a fine pebbled effect, the purpose being to produce a myriad of small light reflecting surfaces in the exterior surface of the glass. In the manufacture of

the globes the exterior surface is treated to produce an iridescent surface which reflects light rays from the globes. The capacity of the iridescent surface to reflect light rays is increased by the slightly roughened surface. 70 The iridescent effect is secured by a treatment of the glass in its manufacture and this iridescence is of such character that when the globe is illuminated from within, the light rays pass outwardly through the 75 glass and the iridescence on the exterior of the glass is temporarily destroyed and disappears. With the globe unilluminated the iridescent exterior of the glass conceals or 80 obliterates the color of the glass and both the "up" and "down" globes will appear to be of the same iridescence without any distinguishing color in the upper and lower globes. When, however, the upper globe is 85 illuminated as indicated in Fig. 3 by lighting the lamp within it the iridescence on the exterior of the globe disappears and the green color of the globe is disclosed. The arrows in the upper illuminated globe will 90 appear green like the body of the globe but of a lighter shade. The arrows will be more brilliantly illuminated than the body of the globe because they are thinner than the body of the globe, thus permitting more light rays to pass through with less absorption than through the thicker part.

In Figs. 6 and 7, the "up" and "down" signals 12 and 13 are in cylindrical form supported on a bracket in the manner of a light fixture. Back of the signals is arranged a mirror 14, said mirror giving an added ornamental appearance to the fixture and giving a more brilliant illumination to the signals when the lamps are lighted.

What I claim is:

1. A directional signal in the form of cover means for a lamp, comprising a translucent signal colored glass member adapted to extend across the lamp and conceal it, means for supporting said glass member in 110 lamp-concealing position, and a direction-indicating character at the inner surface of said glass member, the exterior surface of said member having a signal obscuring light-reflecting iridescent surface to contrast with the aforesaid color of the body of the glass and adapted to conceal both the direction-indicating character and the color of the body of the glass when not illuminated, the exterior color being temporarily 115 destroyed by light passing through the glass from the interior of the cover means, whereby when said glass member is illuminated by the lamp the exterior surface color will disappear, the color of the glass body will 120 be apparent and the signal character will be visible.

2. A directional signal in the form of cover means for a lamp, comprising a translucent signal colored glass member arranged 125

in front of the lamp and having a direction-indicating character impressed in its inner surface whereby the glass outlining said direction-indicating character will be thinner than the body of the glass, for the purpose set forth, the exterior surface of said member being treated so as to have a signal-obscuring, light-reflecting, integral, iridescent surface to contrast with the aforesaid color of the body of the glass and adapted to conceal both the direction-indicating character and the color of the body of the

glass when not illuminated, the exterior color being temporarily destroyed by light passing through the glass from the interior of the cover means, whereby when said glass member is illuminated by the lamp the exterior surface color will disappear, the signal color of the glass body will be apparent and the signal character will be visible. 15 20

In testimony whereof I hereunto affix my signature.

PAUL SCHUYLER VAN BLOEM.
